(57) **CLAIM**

The ornamental design for a trim module, as shown and described.

DESCRIPTION

FIG. 1 is a perspective view of an internal corner trim module in accordance with an embodiment of the present disclosure;

FIG. 2 is a right side elevational view of the internal corner trim module of FIG. 1;

FIG. 3 is a left side elevational view of the internal corner trim module of FIG. 1;

FIG. 4 is a front elevational view of the internal corner trim module of FIG. 1;

FIG. 5 is a back elevational view of the internal corner trim module of FIG. 1;

FIG. 6 is a top elevational view of the internal corner trim module of FIG. 1;

FIG. 7 is a bottom elevational view of the internal corner trim module of FIG. 1;

FIG. 8 is a perspective view of an internal corner trim module in accordance with another embodiment of the present disclosure;

FIG. 9 is a right side elevational view of the internal corner trim module of FIG. 8;

FIG. 10 is a left side elevational view of the internal corner trim module of FIG. 8;

FIG. 11 is a front elevational view of the internal corner trim module of FIG. 8;

FIG. 12 is a back elevational view of the internal corner trim module of FIG. 8;

FIG. 13 is a top elevational view of the internal corner trim module of FIG. 8; and,

FIG. 14 is a bottom elevational view of the internal corner trim module of FIG. 8.

(Continued)

The trim module is shown with a symbolic break in its length. The appearance of any portion of the trim module between the break lines forms no part of the claimed design.

1 Claim, 14 Drawing Sheets
